UNITED STATES PATENT OFFICE.

EDWARD H. BELDEN, OF TOLEDO, OHIO, ASSIGNOR TO THE WILLYS-OVERLAND COMPANY, OF TOLEDO, OHIO, A CORPORATION OF OHIO.

VEHICLE WINDOW.

Application filed July 19, 1922. Serial No. 576,054.

This invention relates to improvements in windows for vehicles, particularly those which can be raised and lowered and are provided with a counterbalance mechanism.

5 It has been found that if the sliding windows, such as for example are used in closed automotive vehicles, fit sufficiently loose in their guides to permit their being readily raised and lowered, the vibration of 10 the vehicle would cause an objectionable rattle of the window in its casing. It is an object therefore of this invention to provide a simple yet effective means for preventing any such rattling of the window, while not 15 materially affecting the ease of its operation. The particular means provided consists of a coil spring connected between the window support and a part of the counterbalance mechanism. Such a spring while admirably 20 adapted to perform the function intended will, unless proper precautions are taken to prevent it, be set vibrating by the vibrations of the vehicle and emit an objectionable "sing". A further object of this invention 25 is the provision of means for eliminating this "sing".

The objects of the invention are accomplished in one instance by the devices and means described in the following specification, but it is evident that the same may be varied widely without departing from the scope of the invention as pointed out in the appended claims.

A structure constituting one embodiment 35 of the invention is illustrated in the accompanying drawing forming a part hereof in which:

Figure I is a side elevation of a vehicle door having a sliding window therein, a portion 40 of the door being broken away to better show the mechanism.

Fig. II is a cross sectional view of a portion of the door taken on the line II-II of Fig. I and

45 Fig. III is a fragmentary view on a larger scale of the spring shown connected to the window in Fig. I.

Similar reference characters refer to corresponding parts throughout the several views, and the sectional view is taken looking in the direction of the arrows at the ends of the section lines.

Referring now to the drawing, there is shown for the sake of illustration, a door 5 of an enclosed automobile having a glass

window 6, slidable in guides 7 formed on the door stiles whereby it is adapted to be raised and lowered as desired. The window may be secured in various positions of adjustment by means of a spring catch 8 engaging in notches 9 in a strip 10 fastened to one of the stiles. A counterbalance device is shown as comprising an arm or lever 12, pivotally connected at 13 to the adjacent door stile and carrying a roller 14 at its opposite end. The roller has a concave face to adapt it to fit the convex outer edge of the lower window frame 15 against which it bears. A coil spring 16 has its opposite ends attached respectively to the lever 12 and to a plate 17 stationary with the door frame. For varying the tension of this spring the lever is provided with several notches 18 at varying distances from its pivoted point and the plate 17 likewise has a number of openings 19 for receiving that end of the spring.

Near its outer or roller end, the lever 12 has a post 20 and the lower strip 15 of the window frame has a hook 21 projecting downward at a point near one end thereof. A coil spring 22 is stretched between the post 20 and the hook 21, it being observed that the post 20 is provided with a groove located substantially in alignment with the window for receiving a loop in the end of the spring. The effect of this spring, which is preferably much weaker than the spring 16 of the counterbalance, is to urge the window at all times against the girder at the left of the door as the same is viewed in Fig. I. The pressure of the spring 22, while insufficient to cause the window to bind in its guides is nevertheless sufficient to prevent all rattling of the window due to vibrations of the vehicle.

The spring 22, while successfully performing the function for which it is intended has under certain circumstances the disadvantages of being set into vibration by the jar or vibration of the vehicle and emitting a disagreeable "sing". It has been found however, that this may be eliminated by enclosing the spring 22 in a bag or tube 24 of fabric such for example, as muslin. As so enclosed the vibration of the spring 22 is so damped as to be no longer objectionable.

While I have shown and described in considerable detail a specific embodiment of my invention, it is to be understood that this showing and description is illustrative only and for the purpose of rendering my inven-

tion more clear, and that I do not regard the invention as limited to the details of construction illustrated or described, nor any of them, except in so far as I have included such limitations within the terms of the following claims in which it is my intention to claim all novelty inherent in my invention broadly as well as specifically.

I claim:

10. 1. In a device of the character described, the combination of guides, a window slidably therein, a counterbalance mechanism for said window, and means connecting said window and said mechanism for reducing vibration of said window in said guides.
2. In a device of the character described, the combination of a pair of guides, a window slidably mounted therein, a counterbalance for said window, and a resilient member connected to said window and said counterbalance and movable with said window and counterbalance for reducing vibration of said window in said guides.
3. In a device of the character described, the combination of a pair of guides, a window slidably mounted therein, a counterbalance for said window comprising a lever engaging the lower side of said window and a resilient member connecting said window to said lever for urging the window against one of said guides.
4. In a device of the character described, the combination of a pair of vertical guides, a window mounted to slide therein, counterbalance mechanism for said window, said mechanism comprising a spring pressed lever having a roller engaging the lower side of said window and a coil spring having one end secured to said lever and its opposite end secured to the lower portion of said window for urging the window against one of said guides.
5. In a vehicle, the combination of guides, a window slidable therein, a counterbalancing support loosely engaging the lower edge of said window at a single point, and means carried by said support urging said window laterally in its own plane for reducing vibration thereof.
6. In a vehicle, the combination of guides, a window slidable therein, a counterbalancing support for said window engaging the lower edge thereof at a point at least one-fourth of the distance inwardly from either end thereof, and means for tilting said window in its own plane upon said support, thereby causing diagonally opposite corners to closely engage said guides to reduce vibration of said window.
7. In a motor vehicle, the combination of window guides, a window slidably mounted therein, a counter-balance for said window, and a spring secured to said counterbalance

and connected with the window and adapted to travel therewith and to urge the window laterally into engagement with one of the guides whereby to reduce vibration of said window.

8. In a motor vehicle, the combination of window guides, a window slidably mounted therein, a counter-balance for said window, a spring secured to said counterbalance and connected with the window and adapted to travel therewith and to urge the window laterally into engagement with one of the guides whereby to reduce vibration of said window, and vibration absorbing means for the spring.

9. In a motor vehicle, the combination of window guides, a window slidably mounted therein, a supporting lever for the window, one end of which is mounted for free movement upon the window, and a spring connected with the window and with the lever and adapted to urge the window laterally upon the lever into engagement with one of the guides whereby to reduce vibration of said window.

10. In a motor vehicle, the combination of window guides, a window slidably mounted therein, a supporting lever for the window, one end of which is mounted for free movement thereon, and a spring connected with the window at the lower edge thereof and with the lever adjacent the free end thereof adapted to urge the window laterally upon the lever into engagement with one of the guides whereby to reduce vibration of said window.

11. In a motor vehicle, the combination of window guides, a window slidably mounted therein, a supporting lever for the window, one end of which is mounted for free movement upon said window, and a spring secured to the free end of said lever and adapted to yieldingly hold the lower end of the window in engagement with one of said guides.

12. In a motor vehicle, the combination of a window frame including guides, a window slidably mounted within the guides, a lever having one end pivoted upon the frame and the opposite end freely engaging the window, a spring connecting the lever with the frame and adapted to urge the free end of the lever upon the window, and a second spring connected with the window and with the lever adjacent the free end thereof and acting to urge said window laterally upon the lever into engagement with one of the guides whereby to reduce vibration of said window.

In testimony whereof, I affix my signature.

EDWARD H. BELDEN.
